UNITED STATES PATENT OFFICE

GEORGE H. NOBBS, OF WATERTOWN, MASSACHUSETTS

WAXING AND POLISHING DEVICE

Application filed August 8, 1928. Serial No. 298,298.

My invention relates to waxing and polishing devices for use upon floors and the like and it has for its object to provide an improved instrument of this class which will be of simple, inexpensive and efficient construction and which can be operated or used to apply wax to and to polish floors and the like expeditiously and at comparatively small cost.

To these ends I have provided a floor waxing and polishing device or instrument comprising a metal container or vessel adapted to receive within it a previously heated element, such as a body of hot water, and to the exterior of which is applied a textile cover or jacket which is heated and pressed against the floor or the like by the water within the container. The container or vessel is made with a flat bottom to conform to the surface to be waxed and polished, and to that portion of the cover or jacket extending across this flat bottom is applied a quantity of wax, which may be in paste form, that is heated and absorbed into the fabric of the cover or jacket so that when the device is seated upon a floor and moved about the hot wax is spread about over the same and evenly distributed.

The cover or jacket is preferably removable so that after applying the wax to the floor the jacket used for that purpose may be removed and a clean jacket or cover substituted and used for polishing the floor after application of the wax as described.

A waxing and polishing device or instrument constructed and operating upon this principle is very efficient; its cost of production is comparatively small and the cost of operation is reduced to a minimum.

Other features and advantages of my invention are hereinafter pointed out.

In the accompanying drawings:

Fig. 1 is a top plan view of a floor waxing and polishing instrument constructed in accordance with my invention.

Figure 2 is a section on line 2—2 of Fig. 1.

Figure 3 is an enlarged section on line 3—3 of Fig. 1.

Figure 4 is a plan view of the felt pad hereinafter referred to.

The container or vessel 1 of my improved

wax applying and floor polishing device is herein shown as a hollow sheet metal vessel of cylindrical shape comprising a circular side wall 1, a top wall 2 and a flat bottom wall 3. The top wall 2 is made with a filler opening or port 4 normally closed by a removable filler cap 5 having threaded engagement with a nipple 6 forming part of the top wall 2 and surrounding the opening 4. The top wall 2 is also made with a bracket or extension 7 to which is pivoted, at 8, the lower end of a handle 9 by means of which the device is manipulated.

In closing the bottom wall 3, the side wall 1 and the marginal portion of the top wall 2, is a cloth bag-like jacket or cover 10 made at its mouth with an annular pocket 11 within which is arranged a draw-string 12. This jacket is secured in position upon the container by means of the draw-string 12 which is drawn tight and its ends tied together as shown in Fig. 1.

Within the jacket 10 between the bottom wall 3 of the container and the bottom of the jacket is arranged a circular felt pad 13 that is formed with a multiplicity of perforations 14 as shown in Figs. 2 and 4.

When the above described device is to be used for waxing a floor or the like the filler cap 15 is removed and the container is filled with a body of hot water 15 after which the filler cap is replaced. Then wax paste is spread over the bottom portion of the jacket 10 and the heat from the water within the container melts the same so that it soaks into and saturates the cloth jacket and also the pad 13.

The device is then placed upon the floor and slid back and forth over the same by means of the handle 9. The body of water 15 provides sufficient weight to hold the device down against the floor with the desired pressure thus relieving the operator of this work, while at the same time heat is radiated downward through the holes 14 to the bottom of the jacket 10 by which it is transmitted to the floor and the wax that is spread upon the latter.

Thus the container with its heated jacket and pad operates to distribute the wax very

uniformly over the floor with little effort on the part of the operator, the heat supplied by the hot water serving to rapidly evaporate the solvent used in the wax thus shortening the time required for drying the wax before polishing.

5 Two covers 10 and two pads 13 are furnished with each container, one cover or jacket and its pad being used exclusively in applying the wax and the other cover and its pad being used exclusively for polishing the floor after the wax has been applied. Therefore, after the application of the wax to the floor the cover and pad used in applying the 10 wax are removed and the other un-waxed cover and pad are applied to the container and the device used to polish the applied wax.

15 The use of hot or boiling water for the dual purpose of furnishing weight or pressure and also heat is advantageous because all liability of burning the jacket, pad or floor is 20 obviated, while the weight of the water makes it unnecessary for the operator to exert downward pressure on the handle either 25 during the waxing operation or during the polishing operation.

Furthermore, when the device is not in use and the container is empty it is light and easily handled or transported.

30 In practice I have found that one filling of the vessel or container with hot water is usually sufficient to supply the heat required for waxing and polishing a house floor of average size.

35 What I claim is:

A device of the character described comprising a vessel made from sheet metal adapted to receive within it and to hold confined therein a body of hot liquid, said vessel being 40 made with a filler opening and having a flat bottom; a removable closure for said opening; a handle pivotally connected at one end with the top of said vessel; an apertured felt pad occupying a position against and covering 45 the outer side of said flat bottom; a bag-like fabric cover within which said vessel and said pad are inclosed, said cover being made adjacent its mouth with a pocket for a draw-string, and a draw-string within said pocket.

50 Signed by me at Boston, county of Suffolk, State of Massachusetts, this 10th day of July, 1928.

GEORGE H. NOBBS.
